Primary Examiner—Bernard Ansher**Assistant Examiner—**P. Hyder**Attorney, Agent, or Firm—**Mason, Fenwick & Lawrence**[57] CLAIM**

The ornamental design for a handle for a tool, as shown and described.

DESCRIPTION

FIG. 1 is a bottom, front and left side perspective view of a handle for a tool showing my new design;

FIG. 2 is a top plan view thereof;

FIG. 3 is a front elevational view thereof, the rear view being a mirror image thereof;

FIG. 4 is a bottom view thereof;

FIG. 5 is a left end view thereof; and,

FIG. 6 is a right end view thereof.

The broken line showing of the bit is for illustrative purposes only and forms no part of the claimed design.

FIG. 1

FIG. 2

FIG. 3

FIG. 4

FIG.5
